UNITED STATES PATENT OFFICE.

NILS DAVID LEVIN, OF COLUMBUS, OHIO, ASSIGNOR TO THE JEFFREY MANUFACTURING COMPANY, A CORPORATION OF OHIO.

ELECTRIC-LOCOMOTIVE CABLE-REELING MECHANISM.

1,247,421.

Specification of Letters Patent.

Patented Nov. 20, 1917.

Application filed July 22, 1911. Serial No. 639,931.

To all whom it may concern:

Be it known that I, NILS D. LEVIN, a citizen of the United States, residing at Columbus, in the county of Franklin and State of Ohio, have invented certain new and useful Improvements in Electric - Locomotive Cable-Reeling Mechanism, of which the following is a specification, reference being had therein to the accompanying drawing.

This invention relates to electric locomotives of the type provided with reels for winding and unwinding electric conductor cables. Locomotives of this class are now well known and are especially adapted for use in coal and similar mines to enter side entries and rooms which are not provided with trolley wires or other permanent conductors. In operation the conductor cable is secured to a trolley wire or other conductor, and current is supplied through the cable to cause the locomotive to advance into a side entry or room. As the locomotive moves forward, the cable is automatically unwound from the reel. When the locomotive returns, current is still supplied through the cable and the cable is automatically rewound upon the reel.

The object of this invention is to provide improved actuating and controlling devices for the reel. With this object in view, the invention consists in the arrangement of parts and in the structural features which are fully set forth in the following specification and claims.

In the accompanying drawings which form a part of the specification I have shown those embodiments of my invention which I now consider preferable, but it will be understood that modifications and changes may be made without departing from the spirit of my invention.

Of the drawings,

Figure 1 is a side elevation of a locomotive embodying one form of my invention.

Fig. 2 is a plan view of the locomotive shown in Fig. 1.

Fig. 3 is an enlarged side elevation of the reel and actuating and controlling mechanism shown in Figs. 1 and 2.

Fig. 4 is a plan view of the construction shown in Fig. 3.

Fig. 5 is a side elevation of a locomotive embodying a modified form of my invention.

Fig. 6 is a plan view of the locomotive shown in Fig. 5.

Referring to the drawings, 1 represents, as a whole, a locomotive which may be of any of the ordinary forms. The locomotive shown is provided with the usual axles and track wheels and is driven by motors 2, 2. At one end of the locomotive are the usual controlling devices such as the brake wheel 3 and the controller 4. At the other end of the locomotive there is located the cable reel mechanism which will now be described in detail.

Referring especially to the constructions in Figs. 1 to 4, 5 represents a main reel frame which is bolted, or otherwise secured, to the main locomotive frame. 6 represents the reel which comprises a center 7 preferably made up of wooden disks and metallic side flanges 8, 8. The parts of the reel are held together by means of the through bolts 9, 9. The reel center is recessed at its ends and in the recesses are secured hubs 10 and 11 which are secured to short stub shafts 12 and 13. One of the stub shafts, as for instance, 12, is mounted in a metallic bearing 14 on the frame 5; the other shaft 13 is mounted in a bearing 15 which is supported on the frame 5 by means of a block 16 of insulating material such as wood.

17 is a bracket extending horizontally from the frame 5. Mounted upon this bracket is a motor 18. A controller 18^a is provided for this motor. The motor is provided with a horizontal shaft 19 carrying a pinion 20. Mounted above the motor, preferably upon the frame thereof, is a horizontal shaft 21 and a driving gear 22 which meshes with the pinion 20. Also secured to the shaft 21 is a sheave 23 adapted to receive and engage with an endless rope 24. This rope also engages with a sheave 25 secured to the end of one of the aforementioned stub shafts, as for instance 12.

Mounted in the frame 5 below and at one side of the reel is a shaft 26 which is preferably stationary. Pivoted near the end of the shaft which is adjacent the sheave 25 is a lever 27 which extends diagonally upward and which carries at its upper end a pulley 28 which is arranged to engage the rope 24 to tighten it. Also pivoted upon the shaft 26 at a point adjacent the lever 27 is an upstanding arm or lever 29. At the upper end of the arm 29 is a brake shoe 30 which is ar-

ranged to engage the periphery of the sheave 25 when the arm 29 is moved. The arm 29 may be moved by means of a lug 31 on the lever 27 which engages with a screw 32 which extends through a threaded aperture in a lateral projection on the arm 29. By adjusting the screw the position of the arm 29 relative to the lever 27 may be regulated.

33 is a rock shaft mounted in suitable bearings in the lower part of the frame 5 and on the opposite side thereof from the shaft 26. At the end of the shaft 33 which is adjacent the lever 27 there is secured an arm 34 provided at its upper end with a pin 35 which extends into and engages with a suitable slot 36 formed in the lever 27. At the other end of the shaft 33 there is an upward extending lever 37 to the upper end of which is pivoted a yoke 38. The yoke 38 is provided with a threaded aperture adapted to receive a threaded rod 39. The rod 39 extends the length of the locomotive and is provided at the operator's end with a hand wheel 40, by means of which it can be moved longitudinally to cause the rope to be tightened or the brake to be applied.

Mounted in bearings on brackets 41, 41 on the frame 5 is a guide mechanism shaft 42 which is double threaded as indicated in Fig. 4. This shaft 42 is driven from the reel by means of a chain 43 which passes over the sprocket wheels 44 and 45. Mounted in a suitable guideway which extends parallel to the shaft 42 is a carriage 46 which is provided to engage with the double threads of the shaft 42 and to be moved by them backward and forward along the shaft. The carriage 46 is provided with guide pulleys 47, 47 and 48, 48.

40 The cable is led in between the guide pulleys on the carriage 46, and if provided with two conductor wires, one of these is connected with the hub 10 and the other with the hub 11. From the hub 10 electrical connection is established through the shaft 12 and the bearing 14 to the metallic parts of the locomotive and to the ground. From the hub 11 connection is established through the brush 49 to the motors 2, 2 and 18.

50 When it is desired to operate the locomotive shown in Figs. 1 to 4 and to make use of the cable reel mechanism, the free end of the cable is secured to a conductor and the locomotive is caused to move in the usual manner away from the conductor. During this movement the cable is unwound from the reel. By means of the hand wheel 40 and the rod 39, the lever 37 and associated parts are maintained in the position shown by dotted lines in Fig. 3. The unwinding of the cable may be controlled by adjusting the retarding force of the brake shoe 30 to suit the conditions. During unwinding it will be understood that the rope 24 is slack. It is, therefore, immaterial

whether or not the motor 18 be in operation during unwinding.

When the locomotive is to return and it is desired to rewind the cable, the lever 37 and associated parts are moved by means of the hand wheel 40 and the rod 39 to the position shown by full lines in Fig. 3; the result being that the brake shoe 30 is moved out of contact with the sheave 25 and that the pulley 28 is moved into position to tighten the rope 24. As a result of the tightening of the rope 24, power is transmitted through it from the motor 18 to the reel 6. The power connection afforded by the rope is a yielding one, and as a result excessive tension on the cable is made impossible. As soon as the cable tension reaches a definite amount the rope will slip on one or the other of the sheaves and prevent further tensioning of the cable. The amount of cable tension may be regulated by adjusting the position of the tightener pulley 28. It will, of course, be understood that during winding, the cable is guided back and forth along the reel by means of the reciprocating carriage 46.

In Figs. 5 and 6 I have shown a modified form of my invention which differs from the form shown in Figs. 1 to 4 in that, power for driving the reel is derived from the main locomotive motors instead of from a separate reel motor. The construction is similar to that I have described with the exception, that the gear 22 is mounted on a stud on the casing of one of the main motors. It derives its power from engagement with an idler gear 22^a which meshes with a pinion 22^b on the motor shaft. The motor 18 is omitted together with its controller 18^a, otherwise the construction is identical with that before described, and further description, therefore, can be omitted.

I am aware that rope drives for cable reels have been heretofore proposed, and I do not, therefore, broadly claim such a drive as a part of my present invention. In earlier devices, use has been made of the rope itself to provide a braking force to resist the rotation of the reel in the unwinding direction. This has resulted in excessive wear upon the rope and by my present invention I have provided a simple and effective means for obviating this wear upon the rope and for placing it upon a specially provided brake shoe.

What I claim is:

1. In a cable reeling mechanism for electric mine locomotives, the combination of a reel on the locomotive frame, an electric cable connected to the reel at one end and adapted to be detachably connected at the other end to a stationary conductor, a power shaft mounted fixedly on lines adjacent to the reel, a normally idle sheave rigid with

- and arranged close to the end of the reel, a sheave on the power shaft, a relatively short rope belt on said sheaves, a rope tightener, a friction brake arranged to engage directly 5 with the reel sheave, and optionally controlled means for pressing the brake without fixed limit into engagement with the reel sheave to increase the retardation thereof indefinitely.
- 10 2. In a cable reeling mechanism for electric mine locomotives, the combination of a reel on the locomotive frame, a cable connected thereto at one end and adapted to be connected at the other end to a stationary
- 15 conductor, a power shaft mounted closely adjacent to the reel, alined rope sheaves on the shaft and the reel respectively, a rela- tively short frictionally acting rope on said sheaves, a rope tightener, a friction brake adapted to directly engage the reel sheaves, 20 means for applying manual power to press the brake without fixed limit against the reel sheave to optionally increase to any desired extent the retarding of the unwinding movement of the reel and simultaneously 25 moving the tightener away from the rope, and means for holding the brake stationary after manual adjustment.
- In testimony whereof I affix my signature, in presence of two witnesses.

NILS DAVID LEVIN.
